UNITED STATES PATENT OFFICE.

JOHN W. GRAVES, OF LITTLE ROCK, ARKANSAS.

LINT-COTTON ACCUMULATOR AND CONVEYER.

SPECIFICATION forming part of Letters Patent No. 633,996, dated October 3, 1899.

Application filed February 8, 1898. Serial No. 669,604. (No model.)

To all whom it may concern:

Be it known that I, JOHN W. GRAVES, a citizen of the United States, residing at Little Rock, in the county of Pulaski and State of Arkansas, have invented certain new and useful Improvements in Lint-Cotton Accumulators and Conveyers; and I do hereby declare the following to be a full, clear, and exact description of the invention, such as will enable others skilled in the art to which it appertains to make and use the same.

My invention relates to certain new and useful improvements in accumulators and conveyers for lint-cotton on its way from the gins to the press.

Prior to my invention in apparatus for feeding the press directly from the gins it has been necessary either to interrupt the action of the gins while the formed bale was being removed from the press or else to provide an additional press, into which the bat was fed without stopping the gins. The first of these expedients involved much loss of time and the second a largely-increased expense because of the very considerable cost of the additional press required.

My invention is designed to obviate the disadvantages of the former practice by permitting a continuous operation of the ginning apparatus during the said periods of inactivity of the press and without necessitating the employment of an additional press. To this end I have devised an apparatus wherein while the press is temporarily out of service the ginning operation proceeds uninterrupted, the cotton from the gins being detained in the meantime on its way to the press and accumulating in a receiver of ample capacity, from which it is subsequently forwarded to the press without interfering with the regularity or harmony of the operation.

In the accompanying drawings, Figure 1 represents a longitudinal vertical section of an apparatus embodying my invention. Fig. 2 represents a top plan view and partial section on a plane indicated by the line 2 2 of Fig. 1. Fig. 3 represents a transverse vertical section on a plane indicated by the line 3 3 of Fig. 1. Fig. 4 represents a section on a plane indicated by the line 4 4 of Fig. 2 and further illustrates in section certain minor details of construction.

Similar figures of reference indicate similar parts throughout the several views.

Referring to the drawings, it will be observed that the apparatus consists, in part, of a main housing provided with outer walls 5 and inner walls 6, leaving an intervening space 7, partitioned at different points, as indicated by dotted lines in Fig. 1, so as to form air and dust discharge conduits opening at their lower ends into the outer air. The inner walls 6, together with the end walls, form an inclosed chamber or lint-room 8, within whose lower portion is located a traveling conveyer, consisting, preferably, of a series of transverse slats 9, secured to endless bands 10, which pass over drums 11, one of which is rotated by means of a pulley 12. I prefer to operate the pulley 12 by a belt from the press-shafting, so that when the press is stopped the pulley is brought to rest likewise, and vice versa; but in any event I contemplate making the rotation of the pulley independent of the ginning apparatus, the condensers, and disintegrators in the sense that it (and consequently the conveyer) may be stopped without interfering with the continued operation of the parts referred to. At the discharge or delivery end of the conveyer 80 is located, in elongated bearings permitting the requisite vertical play, a heavy roll 13, preferably of metal, for compressing the bat as it issues from the apparatus.

Immediately above the traveling conveyer 85 are situated a series of cylinders 14 15 16 17 18 covered with wire-gauze and which rotate in a direction opposed to the travel of the cotton upon the conveyer. They determine the thickness of the bat before its compression by 90 the roll 13, and consequently determine its ultimate thickness in the bale. The tendency of each cylinder is to throw rearwardly all cotton in excess of that which will naturally pass between it and the surface of the 95 conveyer, and I preferably arrange them at gradually-increasing distances above the conveyer, as indicated in Fig. 1, so that the thickness of the bat increases correspondingly as it approaches the compression-roll 13. These 100 cylinders serve as disintegrators for the cotton entering the lint-chamber from the series of superjacent condensing-cylinders 19. The condensing-cylinders are of the same struc-

ture as the disintegrating-cylinders and consist of longitudinal slats spaced apart and secured to end spiders mounted upon actuating-shafts. They are open at their ends and 5 covered with a wire screen of such mesh that the lint-cotton from the air-trunks of the gins will be arrested by the screen, whereas the dust will pass through the screen and out through the open ends of the cylinders into 10 the partitioned air and dust discharge passages intervening between the inner and outer walls of the apparatus. The said cylinders 19 are boxed within casings 20, extending transversely across and within the lint-room 8. They are provided with guards 21 of flexible fabric or the like for excluding the air-current from the lint-room 8 and also with bat-rolls 22, which discharge directly upon the peripheries of the corresponding subjacent 15 disintegrating-cylinders.

The disintegrating-cylinders 14 15 16 17 rotate at a higher speed than the condenser-cylinders, and consequently have a faster peripheral motion. Consequently as the bats 20 from the condensers fall upon the peripheries of the disintegrating-cylinders they are violently projected therefrom and with such energy that the bats are completely broken up and disintegrated, so that in their loosened 25 and disaggregated condition they can be reunited to form a unitary and homogeneous bat below. The peripheral speed of the disintegrating-cylinders I preferably make twice that of the condensing-cylinders, a result 30 which is readily obtained, for instance, by belting each condensing-cylinder to its corresponding disintegrating-cylinder and correspondingly varying the size of the belt-pulleys, as shown.

40 The condenser-cylinders themselves may, as shown, be conveniently actuated the one from the other, one of the series being driven from a pulley on the shaft of the cylinder 18 and said cylinder being driven from the line-shafting by a belt passing over the pulley 23, or any other suitable arrangement may be 45 employed for producing the desired rotation of the several cylinders.

In many instances it will be desirable to 50 employ the apparatus at one time in connection with a set of gins supplying a certain grade of lint-cotton and at another time in connection with a set of gins supplying lint-cotton of a different grade. I have provided 55 for this contingency by supplying each condenser with a duplex lint-conveying flue, the separate branches 24 25 of which lead, respectively, to different gins. These branches merge into one at the entrance to the condenser, and a slide or gate 26, having an operating-handle, is provided adapted to cut off one of the branches from communication with the condenser when the other branch is in service. A flanged cover 27 serves in each 60 case to close the top of the conduit after the slide or gate has been adjusted.

The general operation of the apparatus will

now be apparent. The lint-cotton received from the gins through the particular conduit branches in use is gathered upon the peripheries of the rotating condensers and is fed, in the form of bats, upon the peripheries of the corresponding disintegrating-cylinders, the dust in the meantime passing out through the open ends of the condensers and finally 70 into the outer air. As the condenser-bats fall upon the disintegrating-cylinders they are violently projected therefrom by centrifugal force and are broken up and pulled apart by the energy with which they are acted upon 75 by the rapidly-revolving surfaces. The conveyer having been put in motion in the meantime and the press started the body of disintegrated cotton is carried forward toward the compression-roll and a new and uniformly homogeneous bat begins to form, gradually increasing in thickness for the reason 80 that the disintegrating-cylinders throw rearwardly all cotton in excess of that which will naturally pass between their peripheries and the upper surface of the conveyer. When the bat thus formed reaches the discharge or delivery end of the conveyer, it immediately begins to pass beneath the compression-roll and is thereafter continuously fed in a condensed condition to the press until it is desired to stop the press.

When the press is to be stopped for the withdrawal and tying of a formed bale or otherwise, the condensing and disintegrating cylinders are permitted to continue their revolution, but the feed to the press is interrupted by unclutching or otherwise throwing out of action the connection which operates the pulley, thereby bringing the endless conveyer to 105 a standstill. Thereupon the cotton begins to accumulate within the lint-room and around about the disintegrating-cylinders; but this introduces no complication, for the reason that the space is of ample capacity and because the rollers 14 15 16 17 18 act continuously to throw the surplus material rearwardly without permitting it to clog. As soon as the press is again started the conveyer is likewise brought into action, and both may be 110 speeded up, if desired, to temporarily increase the rate of delivery until the lint-room 8 has been relieved of its accumulated excess, whereupon the normal speed may be re-established.

Having thus described my invention, what I claim is—

1. In a cotton accumulator and conveyer, a double-walled housing, the inner walls being separated from the outer by an intermediate space, condenser-cylinders having open ends 125 communicating with said intermediate space, disintegrating-cylinders located below the condenser-cylinders within the lint room or space inclosed by the inner walls, and a bat-compressing conveyer below the disintegrating- 130 cylinders.

2. In a cotton accumulator and conveyer, a double-walled housing, the inner walls being separated from the outer by an interme-

diate space, condenser-cylinders having open ends communicating with said intermediate space, disintegrating-cylinders located below the condenser-cylinders within the lint room 5 or space inclosed by the inner walls, a bat-compressing conveyer below the disintegrating-cylinders, and duplex lint-conveying trunks leading to the condensers.

3. In a cotton accumulator and conveyer, 10 the combination with condensing devices, of a lint-box within which the condensing devices discharge, a disintegrator located below the condenser-cylinders for breaking up the cotton received from the condensing devices, and a bat conveyer and compressor for 15 combining the disintegrated cotton into a unitary bat.

4. In a cotton accumulator and conveyer, the combination with condensing-cylinders, 20 of a lint-box within which the condensing-cylinders discharge, disintegrating-cylinders located below the condenser-cylinders for breaking up the cotton received from the condensing-cylinders, and a bat conveyer and 25 compressor.

5. In a cotton accumulator and conveyer, the combination with condensing-cylinders, 30 of a lint-box within which the condensing-cylinders discharge, subjacent disintegrating-cylinders for breaking up the cotton received from the condensing-cylinders, and a bat conveyer and compressor, the disintegrating-cylinders being located at successively-increasing 35 distances above the conveyer from the rear toward the discharge end thereof.

6. In a cotton accumulator and conveyer, the combination with condenser-cylinders, of disintegrating-cylinders located below the condenser-cylinders and receiving the cotton 40 from the condensers upon their peripheries, and means for imparting to the disintegrating-cylinders a higher peripheral speed than that of the condensing-cylinders.

7. In a cotton accumulator and conveyer, 45 the combination with condenser-cylinders, of disintegrating-cylinders located below the

condenser-cylinders and receiving the cotton from the condensers upon their peripheries and connecting-gear for driving the disintegrating-cylinders from the condenser-cylinders at an increased peripheral speed. 50

8. In a cotton accumulator and conveyer, a traveling conveyer provided at its discharge end with a bat-compressing roll, and a series of cylinders for determining the thickness of 55 the bat, said cylinders being located above the traveling conveyer and at distances which successively increase toward the delivery end of the conveyer.

9. In a cotton accumulator and conveyer, 60 a traveling conveyer provided at its discharge end with a bat-compressing roll, and a series of cylinders for determining the thickness of the bat, said cylinders being located above the traveling conveyer and means for rotating 65 each cylinder of the series in a direction opposed to the travel of the cotton on the conveyer.

10. In a cotton accumulator and conveyer, a traveling conveyer provided at its discharge 70 end with a bat-compressing roll, and a series of cylinders for determining the thickness of the bat, said cylinders being located above the traveling conveyer and at distances which successively increase toward the delivery end 75 of the conveyer, and means for rotating the cylinders in a direction opposed to the travel of the cotton on the conveyer.

11. In a cotton accumulator and conveyer, 80 a conveyer, a compressor-roll at the discharge end thereof, bat-forming cylinders above the conveyer and means for rotating them in opposition to the travel of the cotton upon the conveyer, and means for interrupting the travel of the conveyer without stopping the 85 rotation of the cylinders.

In testimony whereof I affix my signature in presence of two witnesses.

JOHN W. GRAVES.
